CLAIM

The ornamental design for an antenna mount, as shown and described.

DESCRIPTION

FIG. 1 is a top and front perspective view of an antenna mount showing our new design;

FIG. 2 is a top plan view thereof;

FIG. 3 is a right side elevational view thereof, the rear being a mirror image;

FIG. 4 is a right side elevational view thereof, the left side being a mirror image; and

FIG. 5 is a bottom plan view thereof.

The broken line showing of the antenna in FIG. 1 is for illustrative purposes only and forms no part of the claimed design.

FIG. 1

FIG. 2

FIG. 3

FIG. 4

FIG. 5
